F. REGERO

FOUNTAIN PEN

Filed Aug. 14, 1922

Inventor:

Frank Regero

By

Albert Salas

Attest: 14

UNITED STATES PATENT OFFICE.

FRANK REGERO, OF MACON, GEORGIA.

FOUNTAIN PEN.

Application filed August 14, 1922. Serial No. 301,750.

To all whom it may concern:

Be it known that I, FRANK REGERO, a citizen of the United States, residing at Macon, in the county of Bibb and State of Georgia, have invented or discovered certain new and useful Improvements in Fountain Pens, of which the following is a specification, reference being had therein to the accompanying drawing.

This invention relates to so-called self-filling fountain pens, and consists in certain improvements in the fountain pen covered by my Patent No. 1,398,800, dated November 29, 1921. In the construction shown in my said patent the valve which enables the ink chamber of the pen to be filled when the pump or piston sleeve is drawn out, is opened and closed by longitudinal movements of a valve sleeve; in the present construction this opening and closing of the valve sleeve is effected by a partial rotary movement thereof.

In the accompanying drawings Figs. 1 and 2 are sectional views of a fountain pen embodying the present invention, the parts being in different positions in the two views. Fig. 3 is an end view of the rotatable valve sleeve, and Fig. 4 a side view of the same. Fig. 5 is a detail view of the pen-holding part showing the sleeve on which the valve sleeve is mounted. Fig. 6 is an elevation of a locking sleeve for the rotatable piston or pump, and Fig. 7 is a section of the same. Figs. 8 and 9 are cross sections on lines 8—8 and 9—9 of Figs. 1 and 2, respectively.

Referring to the drawing, 12 denotes the outer casing for the pen, and 13 the pen-holding part mounted at the forward part of said outer casing and preferably having a screw-threaded connection therewith. The part 13 has at its inner end a tubular extension or sleeve 15 having one or more openings 16. Mounted for partial rotation on the tubular extension or sleeve 15 is a valve sleeve 17 having one or more openings 18 which, by partial rotation of said sleeve, may be brought into register with the openings 16 in the extension sleeve 15. Attached to the extension or sleeve 15 is a tube 15^a the interior of which communicates with the chamber of the pen-holding part 13 and with the chamber of the piston or pump sleeve 21. The valve sleeve 17 is provided with side or radial lugs or wings 19 adapted to be engaged by notches 20

formed at the inner end of the piston or pump sleeve 21 when the parts are in the position shown in Fig. 1, so that by giving a partial rotation to the said piston or pump sleeve the valve sleeve 17 may be partially rotated to bring its opening or openings out of register with the opening or openings in the tubular extension 15 for the purpose of closing the valve afforded by said valve sleeve and tubular extension, when the pen is to be filled. After the piston sleeve 21 has been drawn out, as denoted in Fig. 2, for the purpose of filling the chamber of the pen, and has been returned to its former position, as shown in Fig. 1, the valve sleeve 17 will again be given a partial rotation for the purpose of opening the valve.

For preventing disengagement of the valve sleeve 17 from the tubular extension 15 the said tubular extension is provided with an annular groove 22 for the reception of a pin 23 inserted in said valve sleeve and entering said groove.

For the purpose of locking the parts in the position shown in Fig. 1 a sleeve 24 is screwed into the outer end of the casing 12, said sleeve being provided with one or more bayonet joint slots 25 entered by a pin or pins 26 carried by a knob 21^b secured to or integral with the piston or pump sleeve 21 and closing the outer end thereof. Thus when the said piston or pump sleeve is given a partial rotation by turning said knob, for the purpose of closing the valve afforded by the valve sleeve 17 and the tubular extension 15, on which said valve sleeve is mounted, the said pin or pins will be brought into register with the longitudinal parts or notches of the said bayonet slots, thereby enabling the piston or pump sleeve to be drawn out, as shown in Fig. 2, for the purpose of filling the pen. When the said piston sleeve is returned to the position shown in Fig. 1 and the chamber of the pen has been filled with ink, the said knob will be partially rotated in an opposite direction to enter the said pin or pins into the circumferential portion or portions of said bayonet joint slot or slots, thus locking said piston sleeve against longitudinal movement.

The sleeve 24 is preferably provided with a circumferential flange 24^a abutting against the end of the casing 12 when said sleeve is screwed into place, and the outer part of said sleeve is preferably screw-threaded for 110

the reception of a cap 14 affording a housing for the knob 21^a and giving a proper finish to the outer end of the pen casing.

To make a tight joint at the outer end of the ink chamber within the outer casing part 12, a bushing 27 of cork or other suitable material is tightly fitted within said casing contiguous to the sleeve 24, and said bushing is preferably retained in place, against inward movement, by a washer 28 of hard rubber or other suitable material abutting against a shoulder at 12^a formed on said casing part.

To fill the pen the cap 14 is unscrewed from the casing 12 and the piston or pump sleeve 21 is then unlocked from the holding sleeve 24 by a partial rotation of the knob 21^b, causing the ends of the locking pin 26 to register with the longitudinal parts of the bayonet joint slots 25. This partial rotation of the said knob and the piston or pump sleeve therewith closes the valve afforded by the openings 16 and 18 in the parts 15 and 17, and the piston or pump sleeve 21 is then drawn out to fill the ink chamber of the pen. In thus filling said ink chamber the ink flows into the chamber of the piston or pump sleeve 21, and thence into the chamber of the casing 12. When the said piston or pump 21 is forced inward more or less air escapes through the tube 15^a communicating with the chamber of the pen-holding part 13 and the inlet and outlet with which said part 13 is provided.

From the foregoing it will be understood that the present invention affords an improved construction of the valve and valve-operating devices which are deemed to be preferable to the constructions shown in my said Patent No. 1,398,800, hereinbefore referred to.

Having thus described my invention I claim and desire to secure by Letters Patent:

1. In a fountain pen, the combination with an outer casing affording an ink chamber, of a valve comprising two sleeves provided with openings, one of said sleeves being fixed relative to the pen-holding member and the other being rotatable on said fixed sleeve to enable said openings to register with each other, when desired, a piston sleeve slidably mounted within said casing, and means whereby said valve may be opened or closed by a partial rotation of said piston sleeve.

2. In a fountain pen, the combination with an outer casing affording an ink chamber, of a sleeve fixed within said casing and provided with one or more openings, a rotatable valve sleeve mounted on said fixed sleeve and also provided with one or more openings which may be caused to register with the opening or openings in said fixed sleeve, said valve sleeve having side projec-

tions, a piston sleeve fitted to slide within said casing and having a closed outer end, said piston sleeve having means adapted to engage the said projections to enable said valve sleeve to be partially rotated by said piston sleeve, and means for locking said piston sleeve against longitudinal movement.

3. In a fountain pen, the combination with an outer casing affording an ink chamber, of a sleeve fixed within said casing and provided with one or more openings, a rotatable valve sleeve mounted on said fixed sleeve and also provided with one or more openings which may be caused to register with the opening or openings in said fixed sleeve, said valve sleeve having side projections, a piston sleeve fitted to slide within said casing and having a closed outer end, said piston sleeve having means adapted to engage the said projections to enable said valve sleeve to be partially rotated by said piston sleeve, and means for locking said piston sleeve against longitudinal movement, said locking sleeve consisting of a sleeve fixed to said outer casing and provided with a bayonet joint slot or slots, and one or more pins, connected with said piston sleeve and adapted to enter said slot or slots.

4. In a fountain pen, the combination with an outer casing affording an ink chamber, of a valve comprising two sleeves provided with openings, one of said sleeves being fixed relative to the pen-holding member and the other of said sleeves being rotatable on said fixed sleeve to enable the valve to be opened and closed, a piston sleeve slidably mounted within said casing, means whereby said valve may be opened and closed by a partial rotation of said piston sleeve, and means for locking said piston sleeve against longitudinal movement.

5. In a fountain pen, the combination with an outer casing affording an ink chamber, of a valve comprising two sleeves provided with openings, one of said sleeves being rotatively mounted on the other to enable the valve to be opened and closed, a piston sleeve slidably mounted within said casing, means whereby said valve may be opened and closed by a partial rotation of said piston sleeve, and means for locking said piston sleeve against longitudinal movement, said locking means comprising a sleeve screwed into the outer end of said casing and provided with a circumferential flange and with a bayonet joint slot or slots, and one or more pins connected with said piston sleeve and entering said slot or slots.

6. In a fountain pen, the combination with an outer casing affording an ink chamber, of a valve comprising two sleeves provided with openings, one of said sleeves be-

ing rotatively mounted on the other to enable the valve to be opened and closed, a piston sleeve slidingly mounted within said casing, means whereby said valve may be 5 opened and closed by a partial rotation of said piston sleeve, means for locking said piston sleeve against longitudinal movement, said locking means comprising a sleeve screwed into the outer end of said 10 casing and provided with a circumferential flange and with a bayonet joint slot or slots, said piston sleeve being provided with a knob closing its outer end, one or more pins carried by said knob and entering said slot 15 or slots, and a cap fitted to the outer end of said locking sleeve and affording a housing for said knob.

5. In a fountain pen, the combination

with an outer casing affording an ink chamber, of a valve comprising two sleeves provided with openings, one of said sleeves being rotatively mounted on the other to enable the valve to be opened and closed, a piston sleeve slidingly mounted within said casing, means whereby said valve may be 20 opened and closed by a partial rotation of said piston sleeve, means for locking said piston sleeve against longitudinal movement, a packing bushing within said casing contiguous to said locking sleeve, and 25 means for preventing said bushing from being displaced inwardly in said casing.

15 or slots, and a cap fitted to the outer end of said locking sleeve and affording a housing for said knob.

6. In testimony whereof I affix my signature.

FRANK REGERO.
